Primary Examiner — Phillip S Hyder(74) *Attorney, Agent, or Firm* — Tomlinson McKinstry, P.C.(57) **CLAIM**

The ornamental design for a gut hook bladed pipe slitter, as shown and described.

DESCRIPTION

FIG. 1 is a left side view of our design, the right side being a mirror image;

FIG. 2 is a top view thereof, the bottom being a mirror image;

FIG. 3 is a front top left perspective view thereof;

FIG. 4 is a front left perspective view thereof;

FIG. 5 is a front top left perspective view thereof; and,

FIG. 6 is a front view thereof.

The broken lines depict portions of the gut hook blade pipe slitter in which the design is embodied that are not considered part of the claimed design.

1 Claim, 6 Drawing Sheets(56)
